(57) **CLAIM**

The ornamental design for a tool for a firearm, as shown and described.

DESCRIPTION

FIG. 1 is a front view of the tool for a firearm of our new design;

FIG. 2 is a rear view thereof;

FIG. 3 is a left view thereof;

FIG. 4 is a right view thereof;

FIG. 5 is a top view thereof;

FIG. 6 is a bottom view thereof;

FIG. 7 is a top front perspective view thereof;

FIG. 8 is a bottom front perspective view thereof;

FIG. 9 is a top rear perspective view thereof;

FIG. 10 is a bottom rear perspective view thereof.

FIG. 11 is a front view of the tool with opening bottom cap thereof.

FIG. 12 is a rear view of the tool with opening bottom cap thereof.

FIG. 13 is a left view of the tool with opening bottom cap thereof.

FIG. 14 is a right view of the tool with opening bottom cap thereof.

FIG. 15 is a top view of the tool with opening bottom cap thereof.

FIG. 16 is a bottom view of the tool with opening bottom cap thereof.

FIG. 17 is a top front perspective view of the tool with opening bottom cap thereof;

FIG. 18 is a bottom front perspective view of the tool with opening bottom cap thereof;

FIG. 19 is a top rear perspective view of the tool with opening bottom cap thereof;

FIG. 20 is a bottom rear perspective view of the tool with opening bottom cap thereof; and,

FIG. 21 is another bottom rear perspective view of the tool with opening bottom cap thereof.

The broken lines in the drawings depict unclaimed portion of the tool, and formed no part of the claimed design.

1 Claim, 11 Drawing Sheets
